UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

ROOF-DECK FOR VEHICLES.

1,346,203.

Specification of Letters Patent.

Patented July 13, 1920.

Application filed March 29, 1917. Serial No. 158,456.

To all whom it may concern:

Be it known that I, MATTHEW R. HULL, a citizen of the United States, residing at Connersville, in the county of Fayette and State 5 of Indiana, have invented certain new and useful Improvements in Roof-Decks for Vehicles, of which the following is a specification.

This invention relates to improvements in 10 vehicle tops having rigid decks, such as are commonly used in automobile construction in both stationary and demountable types, having a plurality of transverse bows or frame members several inches in depth, covered with a tight roof on top and ceiled on the inside below, thus forming empty 15 enclosures bounded by the roof and ceiling at top and bottom, and by the transverse bows on the sides.

20 The object of this invention is, first, to utilize one or more of these vacant spaces by providing hinged doors in the ceiling for access thereto. Second, to provide receptacles for the storage of flexible side curtains where the latter will always be 25 convenient and quickly accessible in case of sudden showers which often occur during the warm months when such curtains are used, and third, to provide such a storage place so 30 located that the curtains may be folded therein without removing them from the wires on which they are strung and supported.

I accomplish the above and other objects 35 which will hereinafter appear, by the mechanism illustrated in the accompanying drawing, in which—

Figure 1, is a perspective view of an automobile body having a rigid deck, the 40 otherwise open sides of which are shown closed by flexible and foldable side curtains. Fig. 2 is a section on the line 2—2 of Fig. 1, looking up at the ceiling which is broken away in part. My invention is shown in 45 the top illustrated in this view. Fig. 3 is a perspective view of a portion of the ceiling and top showing the door in open position with the curtains or other contents removed, and Fig. 4 is a vertical section on the line 50 4—4 of Fig. 2.

Like characters of reference indicate like parts throughout the several views of the drawing.

The body 5 is of any usual and suitable 55 construction and the top may be rigidly

built thereto or it may be demountable. It comprises a rigid deck 6, which is supported in front by the windshield posts 7, 7, or in any suitable way, and the rear end of the deck is supported by the usual end panel 8, 60 which generally extends for a short distance forward on each side as shown.

The frame of the deck comprises the longitudinal outside rails 9, 9, which are connected by a series of transverse bows 10, to 65 which a roof 11 is fastened with nails, or by other well known means, and is made water tight in the usual manner. The bows are covered on the inside of the top with a cloth ceiling 12, or other suitable material 70 which hides the bows and completes the closure of spaces between the bows which have heretofore been allowed to remain empty. One or more of these spaces are employed for a curtain repository which is made accessible for use by making a door 13 in the ceiling. The adjacent bows are preferably rabbeted to let the door close in flush with the rest of the ceiling. The doors are built 75 light and strong as here shown, on a frame 80 comprising an edge wire 14 covered on both sides with cloth as shown in Fig. 3, and stiffened with cross slats 15. The opposite edge of the door from its hinge is provided with a series of spring sockets 16 to receive 85 corresponding studs 17 in the rabbeted edge of the bow upon which the door closes whereby the door will be held at numerous 90 points when closed by fasteners which may be loosened by pulling down on the door. To aid in the latter operation, finger pulls 18, one at each spring socket, are provided.

The curtain repository is preferably located near the front end of the ceiling and will contain the flexible and foldable curtains 19, 95 of usual construction. The curtains will be duplicated for the two sides of the vehicle. Each will be strung on a separate cable or wire 20, fastened at one end in a suitable manner, and entering the curtain repository 100 through a suitable hole through its front bow. A spring 21 is introduced into the cable line to enable the line to be drawn taut and fastened in that condition to a hook 22 in the panel 8 at the rear of the top. 105 The line is provided with a suitable end loop to engage the hook.

When not in use the curtain is along the transverse line shown in Fig. 1 and is pushed forward on its wire cable to the curtain re- 110

pository into which it is laid in folded condition, and is there retained by straps 24, in the manner shown in Fig. 4, and the bare wire cable on which the curtain was strung, 5 in use, is folded into the curtain receiving repository with the curtain. One end of each strap 24 is fastened inside of the receptacle and preferably near the side to which door 15 is hinged, so that while the door and folded bundle of curtains not only 10 will swing downwardly in the same general direction, it enables the folded bundle of curtains to be lifted into the receptacle in closing the door, which operation can be effected with one hand while the vehicle is 15 in motion and leaving the other hand of the operator free to operate the steering wheel. It also has a stud and the other end of the strap has a spring socket to engage 20 the stud and fasten the ends of the strap together, as when the strap is wrapped around a folded curtain. The strapped and folded curtain will drop out of the box when the door is opened, making the fastened ends of 25 the straps accessible for their undoing and release of the curtain on short notice.

While the location of the curtain repository near the front of the ceiling of the top is preferable for convenience, it may 30 obviously be located farther back, and at the opposite end, if desired, without departing from the spirit of this invention, and the receptacles in the roof of the car may be used for other than curtain storage.

35 The manner of stringing the curtains on the wire cables is shown in Fig. 2, where it will be seen that the several folds at the front end are not threaded on account of the cables passing under the ceiling from 40 the curtain repository to the windshield.

45 While I have described my invention with more or less minuteness as regards construction and arrangement, I do not desire to be bound thereto any more than is pointed out in the claims.

I claim—

50 1. A vehicle top, comprising a frame, a roof for covering said frame, a ceiling forming the inner covering for said frame and having an opening therein which communicates with a curtain repository formed between said roof and ceiling, a door for closing said opening in the ceiling, curtain-holding straps, means for attaching one 55 end of each strap adjacent the side of the

repository to which the door is hinged, and means for detachably securing the free ends of the straps within said repository.

2. A vehicle top comprising a frame, a roof for covering said frame, a ceiling forming the inner lining for said frame and having an opening therein which communicates with a curtain repository formed between the roof and ceiling, a door for closing said opening, curtain-holding straps, 60 means for securing one end of each strap within the repository to cause the straps when detached at one end to hang suspended adjacently to the open hanging door, and means for removably securing the free 65 ends of the straps within said repository.

3. A vehicle top comprising a roof, a ceiling and transverse members separating and uniting the other two, said parts together forming a curtain repository, a door 75 hinged in the ceiling and affording access to said curtain repository, curtain holding straps, means for securing one end of the straps near the side of the repository to which the door is hinged to cause the closing door to lift the straps and curtains into 80 said repository, and means for detachably securing the free ends of the straps at the will of the operator.

4. A vehicle top comprising a roof, a 85 ceiling and transverse members separating and uniting the other two, said parts together forming compartments, a door in the ceiling affording access to a compartment, a cable adapted to be strung in a taut condition longitudinally of the top close to a 90 side of the top, said cable entering said compartment and passing out through the door-opening thereof, a curtain strung on said cable and adapted to be folded with the 95 cable into the compartment for storage and to be suspended in use from the taut cable, and straps removably secured at their ends, said straps being fastened in said compartment and adapted to hold the folded curtains. 100

In witness whereof I have hereunto set my hand and seal at Connersville, Indiana, this 20th day of March, A. D. one thousand nine hundred and seventeen.

MATTHEW R. HULL. [L. S.]
